(57) **CLAIM**

We claim the ornamental design for a bottle, substantially as shown and described.

DESCRIPTION

FIG. 1 is a top, right, front isometric view of a first embodiment of a bottle.

FIG. 2 is a bottom, right, front isometric view of the bottle of FIG. 1.

FIG. 3 is a front elevation view of the bottle of FIG. 1.

FIG. 4 is a rear elevation view of the bottle of FIG. 1.

FIG. 5 is a right side elevation view of the bottle of FIG. 1.

FIG. 6 is a left side elevation view of the bottle of FIG. 1.

FIG. 7 is a top plan view of the bottle of FIG. 1.

FIG. 8 is a bottom plan view of the bottle of FIG. 1.

FIG. 9 is a top, right, front isometric view of a second embodiment of the bottle.

FIG. 10 is a bottom, right, front isometric view of the bottle of FIG. 9.

FIG. 11 is a front elevation view of the bottle of FIG. 9.

FIG. 12 is a rear elevation view of the bottle of FIG. 9.

FIG. 13 is a right side elevation view of the bottle of FIG. 9.

FIG. 14 is a left side elevation view of the bottle of FIG. 9.

FIG. 15 is a top plan view of the bottle of FIG. 9; and,

FIG. 16 is a bottom plan view of the bottle of FIG. 9.

The broken lines in the drawings illustrate the portions of the bottle that form no part of the claimed design. The stippling in FIGS. 1–4 & 7 represents a contrast in appearance.

1 Claim, 12 Drawing Sheets
